Attorney

UNITED STATES PATENT OFFICE.

MARTIN BLUM, OF COLUMBUS, OHIO.

CLOTHES-BOILER.

1,235,101.

Specification of Letters Patent. Patented July 31, 1917.

Application filed February 10, 1917. Serial No. 147,751.

To all whom it may concern:

Be it known that I, MARTIN BLUM, a subject of the King of Hungary, residing at Columbus, in the county of Franklin and 5 State of Ohio, have invented certain new and useful Improvements in Clothes-Boilers, of which the following is a specification.

This invention relates to certain new and useful improvements in clothes boilers.

10 The primary object of the invention is the provision of a clothes boiler provided with a sudsing arrangement whereby the boiling of the sudsing fluid exerts a sudsing effect upon the contents of the device.

15 A further object of the invention is the provision of a sudsing insert for clothes boilers comprising a member, that may be easily and cheaply manufactured, readily positionable within a receptacle whereby 20 the boiling fluid is caused to rise and be ejected upon the contents of the boiler.

25 In the drawings forming a part of this application and in which like designating characters refer to corresponding parts throughout the several views:

Figure 1 is a central longitudinal sectional view through the device, a portion of the insert member thereof being shown in side elevation,

30 Fig. 2 is a top plan view of one-half of the same with the cover removed, and

Fig. 3 is a transverse sectional view taken through a portion of the insert member.

The device is designed for assisting in the 35 boiling and cleansing of clothes and similar articles, the articles being positioned within a receptacle or boiler 10 provided with a cover or lid 11 of the usual construction, the insert member 12 being arranged therein 40 seated upon the bottom 13 of the boiler.

The insert member 12 consists of an inverted pan-shaped base 14 having a foraminous upper side 15 supported by an elliptical flange member 16 seated upon the bottom 45 13, it being evident that any fluid within the boiler 10 will enter the base through the perforations 17 in the top 15 thereof, while the clothes or articles within the boiler will be positioned upon said top plate 15 of the base.

50 Tubular posts or goose-necks 18 are ar-

ranged upon the opposite ends of the plate 15 communicating with the interior of the base 14, the said posts being rectangular in cross-section and tapering toward their free 55 ends which are arranged with inwardly projecting hooks 19 provided with open mouths or nozzles 20 at the ends thereof.

Alternately arranged upwardly inclined baffle plates 21 are provided within the 60 posts 18, and it will be understood that the fluid within the boiler 10 upon being boiled within the base 14, will rise in the posts 18, and the steam and water will be ejected 65 from the nozzles 20 downwardly upon the articles and fluid which are positioned upon the base 14. The steam and boiling fluid passing upwardly through the posts 18 engage the baffles 21, which cause the fluid passing therethrough to take a tortuous 70 course, while the engagement of the liquid with the baffles assists in effectively mixing and sudsing the fluid prior to its ejection from the nozzles 20.

Handles 22 are provided upon the ends of 75 the boiler 10, while a handle 23 is arranged upon the cover 11, a serviceable clothes boiler is arranged in which the insert portion 12 may be readily removed while the same may be employed with different 80 receptacles or boilers of the general form of the boiler 10 herein illustrated, the action of the insert being to assist in the mixing of the cleansing fluid and the consequent sudsing thereof as well as the projection of 85 the same under pressure upon the articles to be cleaned.

What I claim as new is:

A clothes-boiler having arranged therein 90 an open-bottomed receptacle, with a foraminous top, said top having openings therethrough at its ends, imperforate upright tubular members with their upper ends turned inwardly and downwardly, said tubular members communicating with the openings 95 in the foraminous top, and having arranged therein in staggered relation inwardly and upwardly inclined deflectors to retard the outward flow of the fluid through said tubular members.

100 In testimony whereof I affix my signature.

MARTIN BLUM.
